DESIGN FOR A SPOON OR OTHER ARTICLE OF FLATWARE

Eleanor M. Forbes, San Francisco, Calif., assignor
to S. & G. Gump Co., a corporation of California

Application May 28, 1937, Serial No. 69,604

Term of patent 14 years

To all whom it may concern:

Be it known that I, Eleanor M. Forbes, a citizen of the United States, residing in the city and county of San Francisco and State of California, have invented a new, original, and ornamental Design for a Spoon or Other Article of Flatware, of which the following is a specification, reference being had to the accompanying drawing, forming a part thereof.

In the accompanying drawing:

Fig. 1 is a front elevation of a spoon or other article of flatware, embodying my invention;

Fig. 2 is a side elevational view of a fragmentary portion of the spoon handle; and

Fig. 3 is a sectional view taken on the line 3—3 of Fig. 1.

I claim:

The ornamental design for a spoon or other article of flatware, substantially as shown.

ELEANOR M. FORBES.
